UNITED STATES PATENT OFFICE.

WALTER ROWLANDS, OF MONTREAL, CANADA, ASSIGNOR TO EDMUND
BRISTOL, OF TORONTO, CANADA.

HEAD-CHAIR FOR STUB-SWITCHES.

SPECIFICATION forming part of Letters Patent No. 664,436, dated December 25, 1900.

Application filed May 24, 1900. Serial No. 17,884. (No model.)

To all whom it may concern:

Be it known that I, WALTER ROWLANDS, 5
mechanical engineer, of the city of Montreal,
in the county of Hochelaga, Province of Quebec,
Canada, have invented certain new and
useful Improvements in Head - Chairs for
Stub-Switches, of which the following is a
specification.

The object of my invention is to devise an
10 efficient head-chair for stub-switches which
will be simple in construction and possess the
smallest possible number of parts; and it consists,
essentially, of a plate provided with an
15 integral transverse rib to hold apart the rail
ends, stamped or cast lugs to limit the play of
the switch-rail, and lugs or brackets formed on
or secured to the plate in position to engage
20 the ends of the track-rails opposite which the
switch-rail moves, the whole being constructed
in detail substantially as hereinafter more
specifically described.

Figure 1 is a perspective view showing my
improved head-chair with two track - rails
25 clamped in position therein. Fig. 2 is a per-
spective detail showing my device as arranged
with single clips for the track-rail bases.

In the drawings like letters of reference indicate corresponding parts in both figures.

A is the base-plate of the chair, on which
30 is formed the transverse rib B, either by casting
or rolling.

C indicates two lugs stamped up out of the
metal of the plate to form stops between which
the toe of the switch-rail may play.

D indicates clips preferably stamped up out
35 of the metal of the base-plate and adapted to
engage opposite sides of the bases of the two
track-rails E. There may be one or more of
these clips at each side of the chair.

F is a block fitted between the ends of the
40 track-rails. Through the webs of the rails
and through this block pass the bolts G, pro-
vided with the nuts a. At each end of the
bolts are placed square washers b. It will be
45 noted that these washers are so proportioned
as to engage the sides of the ends of the clips
D, so that the ends of the track-rails are ef-
fectually prevented from creeping away from
the transverse rib B. Each nut a is prefer-
50 ably provided with a nut-lock c, formed of a
strip of sheet metal clamped between the
washer and the rail and extending out over
the top of the washer, so that it may be bent

down to engage the upper side of one of the
nuts.

In the drawings, d indicates spike-holes, by
means of which the base-plate may be firmly
secured to the tie.

In Fig. 2 I show a single clip D, stamped
up from the base-plate. In this case the square
55 washer b is preferably forked, as shown, to
embrace the clip, so that the engagement of
the clip and washer will prevent the rail from
creeping.

While the base-plates are preferably formed
60 by rolling and stamping, it will be understood,
of course, that the same effect might be pro-
duced by casting, though the same strength
in proportion to weight would probably not
be secured.

70 From the above description it will be seen
that I have devised an efficient head-chair
which possesses very few parts.

What I claim as my invention is—

1. A head-chair for stub-switches comprising
75 a base-plate, a transverse rib formed on
the plate, stops stamped up out of the plate
and adapted to limit the play of the switch-
rail, a clip stamped up out of the plate and
adapted to fit over the outer sides of the bases
80 of the two track-rails, a block separating the
rail ends, a bolt clamping together the rail
ends and said block; and a washer on said
bolt; the aforesaid clip coacting with said
85 washer and thereby preventing the rails from
creeping, substantially as and for the purpose
specified.

2. A head-chair for stub-switches, comprising
90 a base-plate, a transverse rib formed on
the plate, stops stamped up out of the plate
and adapted to limit the play of the switch-
rail, clips stamped up out of the plate and
adapted to fit over the outer sides of the bases
95 of the two track-rails, a block separating the
rail ends, a bolt clamping together the rail
ends and block, and a washer supported by
said bolt, the aforesaid clips coacting with
100 said washer on opposite sides thereof and
thereby preventing the rails from creeping,
substantially as and for the purpose specified.

Montreal, Canada, May 9, 1900.

WALTER ROWLANDS.

In presence of—

E. A. CUNNINGHAM,
EDWARD ROBINSON.
